UNITED STATES PATENT OFFICE.

BERT SEABOLDT, OF NEW YORK, N. Y.

LIQUID-FUEL BURNER.

Application filed March 12, 1925. Serial No. 14,862.

- This invention relates to liquid fuel burners and has for its object to provide a burner which will utilize the velocity of the atomizing agent, as well as the velocity of the liquid fuel in securing a high degree of fineness of atomization in the spray, in order to produce complete combustion; to increase efficiency; and to reduce the consumption of the atomizing agent.
- With these and other objects in view, the invention consists of the novel details of construction and combinations of parts more fully hereinafter disclosed and particularly pointed out in the claim.
- The invention consists of the novel construction hereinafter described and finally claimed.

The nature, characteristic features and scope of the invention will be more fully understood from the following description taken in connection with the accompanying drawings forming part hereof, and in which:

- Fig. 1, is a view in longitudinal section of a burner embodying the invention.
- Fig. 2, is a fragmentary view in central section illustrating a slightly modified form.
- Fig. 3, is a fragmentary view in section, showing a slightly different nozzle arrangement;
- Fig. 4, is a view in cross-section taken upon the line 4—4 of Fig. 3, and

Figure 5 is a cross sectional view as seen on the line 5—5 of Figure 1.

For the purpose of illustrating my invention I have shown in the accompanying drawings two forms thereof which are at present preferred by me since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the reference numeral 1, designates a source of air supply fitted to a head 2 having a horizontally extended, exteriorly screw-threaded neck 3. Extending through the head and neck is an angular passage 4 the outlet end of which is tapped to receive the screw-threaded end of a central, longitudinally extended air pipe 5. Also connected with head 2 is an oil supply pipe 6. This pipe is in communication with an angular passage 7

the outer end of which parallels passage 4 and communicates with a chamber 8 in neck 3. Fitted to the outer end of neck 3 is a pipe 9 which surrounds air pipe 5, a coupling comprising members 10 and 11 being employed for attaching the screw-threaded end of pipe 9 with respect to screw-threaded end of neck 3. Within the space formed between the outer wall of pipe 5 and the inner wall of pipe 9 are a plurality of spaced discs 12 arranged concentrically with respect to pipes 5 and 9. The discs may be regularly spaced and are mutilated as at 13 for the passage of oil.

Referring now to right hand end of Fig. 1, a description will be given of the nozzle for creating a mixture of oil and air for atomization prior to delivery for combustion. The air pipe 5 has screw-threaded to its outer end an inner nozzle 15 adapted for longitudinal adjustment. The outer end thereof is provided with an elongated, very minute orifice 16. Surrounding the inner nozzle is an outer nozzle 17 having a bevelled inner wall 18 and an elongated orifice 19 arranged for alignment with orifice 16. The nozzle 17 is connected to the oil pipe by means of a coupling 20 and is normally maintained in fixed position with its bevelled, inner wall in juxtaposed relation to the end of the inner nozzle. Any adjustment desired is secured by entirely removing the outer nozzle and moving the inner nozzle either toward or away from the end of the air pipe to increase or decrease the distance between the inner nozzle and the said bevelled inner wall of the outer nozzle when the latter is replaced. Tampering with the inner nozzle by unauthorized persons is thus made rather difficult. It is thus apparent that the oil in its divided state mixes with the air in the atomizing chamber 21 prior to delivery and ignition.

The purpose of this adjustment to increase or decrease the distance between the inner nozzle and the said bevelled inner wall of the outer nozzle and to establish the exact relation between these two members so that the volume and velocity of air emerging from the inner nozzle and escaping through orifice 19 of the outer nozzle will induce the exact flow of oil or liquid fuel direct from the fuel supply tank, which must always be below the level of the burner, that can be thoroughly atomized and mixed with the proper amount of air that will supply the correct

proportion of oxygen to produce complete combustion. This adjustment produces an automatic governor so that irrespective of the air pressure, which may be from one 5 pound up, the correct and exact amount of oil will be introduced into the mixing chamber, thereby maintaining a constant and proper mixture which will produce perfect combustion.

- 10 The relation between the diameter of the hole in the inner nozzle and the diameter of the hole in the outer nozzle is vital to both the proper induction to flow and thorough atomizing and mixing of the oil with the air 15 before emission from the outer nozzle and the absolute, complete combustion of this mixture after emission from the outer nozzle.

The distance from the forward end of the 20 inner nozzle to the said bevelled inner wall of the outer nozzle is also vital. The taper of the outside of the inner nozzle is also important.

Interposed between the rear end of the outer nozzle 17 and the shoulder of coupling 25 20 is a perforated washer 31 containing a number of small holes 32 through which the oil must pass thereby more thoroughly breaking up and atomizing the oil preparatory to mixture with the air.

- 30 In Figs. 3 and 4 vertically disposed nozzles are provided. The oil pipe 9 carries a head 24 into which is screwed said oil pipe. The upper part of this head carries the inner nozzle 25 and the outer nozzle 26 the same adjustable relation of parts being common to them as in the horizontal type before described. Arranged within the head 24 is an angular passage 27 in communication with the air pipe and inner nozzle. Also arranged 40 in the head 24 are a pair of passages 28-29 in communication with the oil pipe and the outer nozzle. Either type of nozzle is applicable to a burner having the discs or spiral spring shown in Figs. 1 and 2 respectively. 45 The orifice construction and bevelled inner wall of the outer nozzle are the same as previously described. Between the inner end of nozzle 26 and the head is a perforated disc 30 similar to disc 21, the operation being the 50 same. In forming my novel liquid fuel burner the orifice of the inner nozzle and the orifice of the outer nozzle have a pre-determined and constant ratio, and the inner nozzle has pre-determined and fixed relation 55 with respect to the inner bevelled surface of the outer nozzle. The orifice of the inner nozzle is smaller than the orifice of the outer nozzle, and the diameters of these orifices are

determined as follows: The selected diameter of the larger or outer orifice is divided by 60 the common divisor 1.552, which gives the desired diameter of the orifice of the inner nozzle. The distance between the free end of the inner nozzle and the inner bevelled surface of the outer nozzle is substantially less than the 65 diameter of the orifice of the outer nozzle as is clearly shown in the drawing. In a preferred form, this distance is one-half the difference between the diameters of the orifices of said nozzles. 70

It will now be apparent that I have devised novel and useful constructions which embody the features of advantage enumerated as desirable in the statement of the invention and the above description and while I have in the present instance shown and described the preferred embodiments thereof which have been found in practice to give satisfactory and reliable results, it is to be understood that the 75 same are susceptible of modification in various particulars without departing from the spirit or scope of the invention or sacrificing any of its advantages. 80

What I claim is:

In a liquid fuel burner, the combination 85 of an imperforate liquid fuel tube, an imperforate air tube concentrically arranged within the first-mentioned tube, an inner nozzle and an outer concentrate nozzle, means securing said inner and outer nozzles to said inner and outer tubes respectively and establishing communication between said respective nozzles and tubes, said outer nozzle having an elongated cylindrical bore terminating in a tapering bore immediately in advance of its discharge orifice, the discharge 90 orifices of said nozzles being in axial alignment and of substantial axial extent, the orifice of the outer nozzle having a diameter substantially 1.5 times the diameter of the orifice of the inner nozzle, the free end of the inner nozzle being spaced from the wall of the tapering bore of the outer nozzle a distance substantially less than the diameter of the orifice of the outer nozzle, said means for 95 establishing communication between the outer tube and cylindrical bore of the outer nozzle comprising a plurality of passages whose total cross-sectional area is less than that of the annular space between the free 100 end of said inner nozzle and said tapering bore. 105

In testimony whereof, I have hereunto signed my name.

BERT SEABOLDT.
